JAMES PATERSON, OF ELIZABETH, NEW JERSEY, ASSIGNOR TO THOMAS POTTER, SON & CO.

Design No. 4,639, dated February 7, 1871.

DESIGN FOR AN OIL-CLOTH PATTERN.

The Schedule referred to in these Letters Patent and making part of the same.

To all whom it may concern:

Be it known that I, JAMES PATERSON, of Elizabeth, in the State of New Jersey, have invented a new and original Design for Oil-Cloths, and I do hereby declare the following to be a specification thereof.

My design is represented in the accompanying photographic illustration, which forms a part of this specification.

What I claim as my invention and desire to secure by Letters Patent of the United States, is—

The design for an oil-cloth, as shown.

JAS. PATERSON.
